UNITED STATES PATENT OFFICE.

EDWARD S. HOTCHKISS, OF BRIDGEPORT, CONNECTICUT.

ANIMAL-TRAP.

SPECIFICATION forming part of Letters Patent No. 355,016, dated December 28, 1886.

Application filed March 24, 1886. Serial No. 196,369. (No model.)

To all whom it may concern:

Be it known that I, EDWARD S. HOTCHKISS, a citizen of the United States, residing at Bridgeport, in the county of Fairfield and State 5 of Connecticut, have invented certain new and useful Improvements in Animal-Traps; and I do hereby declare the following to be a full, clear, and exact description of the invention, such as will enable others skilled in the art to 10 to which it appertains to make and use the same.

My invention relates to certain novel and useful improvements in the construction of animal-traps, and has for its object to provide such a device as shall be readily cleansed, and 15 which shall be exceedingly economical in cost; and with these ends in view my invention consists in certain details of construction and combination of elements hereinafter set forth, and specifically designated by the claim.

20 In order that those skilled in the art to which my invention appertains may more fully understand the same, I will proceed to describe the construction thereof, reference being had by letter to the accompanying drawings, forming 25 a part of this specification, in which—

Figure 1 is a plan view of my improved trap; Fig. 2, a perspective showing the body of the trap after it has been bent into shape, and Fig. 3 a plan view of the blank from which the trap 30 is formed by bending at the line α .

Similar letters denote like parts in the several figures of the drawings.

A is the body of the trap, B the side, and C the openings through which the bait is reached.

D is a sink formed within the central portion of the body, and within which the coils of the choker-frames are secured.

In manufacturing my improved trap, I first blank out from sheet metal the body desired. The central sink, D, the openings C, and the 40 various perforations for the attachment of the choker-wires may be formed simultaneously with the blanking, or they may be formed after the bending. The blank is cupped up or bent into the shape shown at Fig. 3 by means of 45 dies.

The chief advantages which my improvement possesses are, first, the facility with which the trap may be cleaned; second, the 50 doing away with partitions between the bait-hooks, and, third, the durability and neatness of the trap.

Having thus described my invention, what I claim as new is—

In an animal-trap, the sides and top formed 55 integral from a single blank of sheet metal, said sides having openings cut therein, and the top having a central depression, the trap entirely devoid of interior partitions, substantially as shown and described.

In testimony whereof I affix my signature in presence of two witnesses.

EDWARD S. HOTCHKISS.
